CHILD'S DISH

Harry Pokras, Los Angeles, Calif., assignor to
Merit Products, Inc., Los Angeles, Calif., a cor-
poration of California

Application October 28, 1949, Serial No. 5,745

Term of patent 3½ years

(Cl. D44—15)

To all whom it may concern:

Be it known that I, Harry Pokras, a citizen of the United States, residing at Los Angeles, in the county of Los Angeles and State of California, have invented a new, original, and ornamental Design for a Child's Dish, of which the following is a specification, reference being had to the accompanying drawing, forming a part thereof.

Figure 1 is a perspective view showing my new design for a child's dish.

Figure 2 is a top plan view thereof.

Figure 3 is a side view thereof.

Figure 4 is a bottom plan view thereof.

Figure 5 is a sectional view on the line 5—5 of Figure 2.

I claim:

The ornamental design for a child's dish, sub-
stantially as shown.

HARRY POKRAS.
